DESIGN FOR A DOILY OR SIMILAR ARTICLE

Kenneth C. Hamilton, Milwaukee, Wis., assignor to Milwaukee Lace Paper Company, Milwaukee, Wis., a corporation of Wisconsin

Application June 25, 1942, Serial No. 107,341

Term of patent 14 years

To all whom it may concern:

Be it known that I, Kenneth C. Hamilton, a citizen of the United States, residing at Milwaukee, in the county of Milwaukee and State of Wisconsin, have invented a new, original, and ornamental Design for a Doily or Similar Article, of which the following is a specification, reference being had to the accompanying drawing forming a part thereof.

The single figure of the drawing is a fragmentary face view of a paper doily embodying my new design and showing approximately one-fourth of the design in detail, which design is repeated symmetrically in each of the other three-fourths of the doily. While my design is shown as delineated on a paper doily, it is contemplated that the same may be applied to other similar articles without departing from the spirit of the invention.

The design is an open work shown on a black background to better bring out the details thereof.

I claim:

The ornamental design for a doily or similar article, substantially as shown and described.

KENNETH C. HAMILTON.
